[57] CLAIM

The ornamental design for a dispenser spout, as shown and described.

DESCRIPTION

FIG. 1 is a left, top, frontal perspective view of a dispenser spout embodying my new design;

FIG. 2 is a left side elevational view thereof, which is a mirror image of the right side elevational view;

FIG. 3 is a front elevational view thereof;

FIG. 4 is a rear elevational view thereof;

FIG. 5 is a top plan view thereof; and,

FIG. 6 is a bottom plan view thereof.

The fragmentary broken line representation of a counter top in FIG. 1 is for purposes of illustration only, and forms no part of the claimed design.
